UNITED STATES PATENT OFFICE.

GEORGE HILLARD BENJAMIN, OF NEW YORK, N. Y.

MELTING-FURNACE.

1,401,456.

Specification of Letters Patent. Patented Dec. 27, 1921.

Application filed April 9, 1920. Serial No. 372,633.

To all whom it may concern:

Be it known that I, GEORGE HILLARD BENJAMIN, residing at New York, county of New York, State of New York, have invented certain new and useful Improvements in Melting-Furnaces, of which the following is a specification.

My invention relates to a method of and apparatus for melting and casting metals, especially those of the type where the melting operations do not require the exhibition of a very high temperature, and where the casting is effected at a lower temperature, and where both operations are preferably carried on under conditions where oxydization of the metal or metals (alloys) will not take place, or appreciably affect the metal or metals under treatment.

In practice it has been found that with readily fusible metals, melting is preferably effected at the highest temperature which may be employed without effecting volatilization of the metal, and for the reason that separation of the impurities is best effected under such conditions, and further, that casting can be best effected at a lower temperature than is employed in melting and for the reason the lower the temperature of the metal, the less liability there is for the absorption of oxygen or gases by the metal.

The object of my invention, therefore, is a method of melting and casting and an apparatus, by reason of which the temperature of melting and casting may be regulated as desired, as also the flow of the metal in casting.

The accompanying drawings will serve to illustrate such an apparatus as I find best adapted to carry my invention into effect, in which Figure 1 is a transverse vertical section taken on the line I—I of Fig. 2.

Fig. 2 is a longitudinal vertical section taken on the line II—II of Fig. 1.

Fig. 3 is a transverse vertical section taken on the line III—III of Fig. 2.

Fig. 4 is a longitudinal section taken on the line IV—IV of Fig. 1.

Figs. 5 and 6 are vertical and partial longitudinal sections taken on the same line as

Fig. 2, and illustrating in Fig. 5 the arrangement of a casting apparatus in connection with the furnace structure, and in Fig. 6 the arrangement of a movable metal receptacle in connection with the furnace.

Referring to the drawings, 5 indicates the

melting portion, and 6 the gathering portion of the furnace, both of which may have any suitable construction. The melting portion 5, as shown, consists of the side walls 7, roof 8, end wall 9, and hearth 10. The hearth 10 is inclined downward from each side of the furnace toward a trough 11, which trough portion is inclined from the rear end of the furnace 12 toward the gathering end or portion 6. The gathering end consists of the front and rear walls 13—14, which wall 14 forms the front end of the melting portion 5, side walls 15 and roof 16, and trough 17, which is a continuation of the trough 11, and is arranged at right angles thereto, as shown in Fig. 3. The bottom of the trough 17 is horizontal, and on a level with the forward end of the trough 11. Located within the melting portion are combustion chambers 18—19, adapted to be fed with gas and air through a supply pipe and burners 20, arranged on either side of the furnace. The products of combustion from the combustion chambers are carried upward to air regenerators 21, through suitable flues 22, and thence to the atmosphere through chimneys 23. Air heated by the products of combustion may be employed as usual to heat the air which is combined with gas and introduced into the combustion chambers, the air being carried through the pipes 24 to the air regenerating chambers 21, located on the roof 8 of the melting portion 5, and roof 16 of gathering portion 6, and are, therefore, heated by the outgoing products of combustion and by the heat and conducted through the roofs 8—16. This arrangement, I find to be advantageous. The air regenerators, however, may be otherwise placed. A similar combustion chamber 25 is placed in the gathering portion 6, with similar gas and air burners 26, and similar air regenerators 27. The general arrangement of the combustion chambers, gas burners and air regenerators is substantially similar to that disclosed in my prior Patent 1,268,204, dated June 4, 1918. The only point of difference is the change of position of the air regenerators relative to the roof of the chambers. It will be observed that the combustion chambers 18—19—25 are supported in the upper part of the melting portion 5 and gathering portion 6. I prefer this arrangement, for the reason that when heating chambers are so located the heat effects are more uni-

formly distributed than would be the case if these chambers were otherwise placed.

Situated at intervals on both sides of the melting portion are doors 28, through 5 which the material to be melted may be introduced onto the hearth 10. Situated in front of the gathering portion is a door 29, through which the molten metal in the trough 17 may be ladled out of the hearth if 10 desired.

Referring to Fig. 5: Communicating with the trough 17 is a passage 30, which feeds a measuring device 31, controlled by the slides 32-33. Situated below the measuring device 15 is a casting apparatus which consists of a pillar 34, on which is rotatably mounted a disk 35, carrying molds 36.

Referring to Fig. 6: Communicating with the trough 17 is a passage 30, controlled by 20 a slide 32, and situated under the passage 30 is a receptacle for molten metal 37 on wheeled truck 38 on trackway 39. In the rear end of the furnace is a pipe 40 through 25 which any suitable neutral or reducing gas may be introduced into the body of the melting portion 5 and casting portion 6.

The method employed in operating my improved furnace is as follows:—

The solid metal or alloy is introduced 30 through the doors 28 and under the influence of heat set free from the combustion chambers is melted and flows into the trough 11. Preferably the temperature employed is as high as may be used without effecting volatilization of the metal. The metal when in 35 the trough has a vertical movement in "fining," the impurities gradually rising to the top and the heavier metal sinking to the bottom, and through the inclination of the 40 trough 11 flow to the trough 17 of the gathering portion 6. Any impurities on the surface of the metal in the trough 17 may be removed through the door 29. The temperature of the gathering portion 6 is lower 45 than the temperature in the melting portion 5, and the temperature of the portions 5 and 6 can be regulated by regulating the combustion of gas and air in the chambers 18, 19, 25, or the chamber 25 in the portion 50 6 can be cut out of action so that the only temperature in the portion 6 is that of the heated metal or alloy. The molten metal on the hearth 17 may be ladled through the door 29, or, as shown in Fig. 5, allowing it 55 to flow into the passage 30 and measuring device 31, the slide 33 at the time closed, subsequently the slide 32 closed and the slide 33 opened, when the metal in the measuring device 31 will flow into the mold 36 which 60 at the time is under the measuring device. It will be seen by reason of the arrangement described, that the metal up to the time it is discharged into the mold 36 is kept from contact with the atmosphere and 65 that a measurable amount of metal is delivered as the slides 32 and 33 are manipulated.

In Fig. 6 when the slide is opened any amount of metal up to the capacity of the receptacle 37 may be allowed to flow into the receptacle by manipulating the slide 32. It 70 is manifest that the measuring device and receptacle could be inclosed as indicated in dotted lines, and surrounded by a neutral or reducing atmosphere, so as to prevent any action upon the metal when in a heated condition by the atmosphere.

Having thus described my invention, I claim:

1. In a metallurgical furnace, the combination of a melting portion provided with a trough in the hearth thereof, a gathering portion situated in front of the melting portion and provided with a trough thereof, communicating with the trough of the melting portion, the bottom of the trough of the gathering portion located in the same horizontal plane occupied by the forward end of the trough of the melting portion.

2. In a metallurgical furnace, the combination of a melting portion provided with an inclined trough in the hearth thereof, a gathering portion situated in front of the melting portion, provided with a trough in the hearth thereof and communicating with the trough in the melting portion, said trough 90 collectively forming a single trough.

3. In a metallurgical furnace, the combination of a melting portion, a hearth therefor provided with a hearth inclined from the sides toward the center of the portion, a 100 trough situated between and below the inner ends of the inclined hearth, a gathering portion in front of the melting portion provided with a trough in the hearth thereof and communicating with the trough in the melting portion.

4. In a metallurgical furnace, the combination of a melting portion consisting of a longitudinally arranged chamber, a hearth for such chamber having inclined sides, a 110 trough situated between the inclined sides, a gathering portion consisting of a longitudinally disposed chamber, whose axis is at right angles to the melting chamber, and such chamber situated in front of the melting chamber, a hearth therefor, a trough situated below the hearth and communicating with the trough of the melting portion.

5. In a metallurgical furnace, the combination of a melting portion consisting of a 120 chamber, spaced doors, arranged along each side of the chamber, a hearth having inclined sides, a trough situated between the inclined sides of the hearth, a gathering portion consisting of a chamber, a hearth there- 125 in, a trough beneath the hearth communicat- ing with the trough of the melting portion, and opening in the chamber of the gathering portion through which the fluid metal there- in may be withdrawn.

6. In a metallurgical furnace, the combination of a melting portion consisting of a chamber, a series of combustion chambers therein, means for feeding gas and air to the combustion chambers, a hearth portion, a trough situated in the hearth portion, means for feeding the material to be melted into the chamber, a gathering portion consisting of a melting chamber, a combustion chamber therein, means for feeding said combustion chamber with gas and air, a hearth, a trough in the hearth thereof, and said trough communicating and having its bottom continuous with the trough in the melting chamber.

7. In a metallurgical furnace, the combination of a melting portion consisting of a chamber, means for heating said chamber, a hearth portion, a trough in the hearth portion, a melting portion consisting of a chamber, means for heating said chamber, a trough in the hearth thereof, said trough communicating and having its bottom continuous with the trough in the melting portion.

8. In a metallurgical furnace, the combination of a melting portion consisting of a chamber, a gathering portion consisting of a chamber situated in front of the melting chamber, combustion chambers in said chamber, air regenerator situated over and in contact with the roof of said chamber, and means for feeding gas and heated air into said combustion chambers, together with means for conveying the products of combustion from the combustion chambers through the air regenerator.

9. In a metallurgical furnace, the combination of a melting chamber, a gathering chamber, a casting device situated under the gathering chamber, and means for feeding at intervals, regulated portions of the molten

material from the gathering chamber into the casting device.

10. In a metallurgical furnace, the combination of a melting chamber, a gathering chamber, a casting device situated under the gathering chamber, said casting device consisting of a neutral table carrying mold, and means situated between the bottom of the gathering chamber and the mold whereby regulated quantities of metal may be withdrawn; first into the measuring device, and then discharged into a mold at intervals.

11. The method herein described, which consists in melting and fining, at a determined temperature, in a chamber, delivering the fined metal into a second chamber, maintaining the temperature of the fined metal in the second chamber at a point lower than that of the melting chamber, and withdrawing the fined metal from the bottom of the second chamber, in regulated quantities into molds adapted to receive such metal.

12. The method herein described, which consists in introducing cold metal into a melting chamber at the highest temperature to which the metal may be subjected without volatilization, conveying the fined metal from said chamber into a second chamber, and maintaining the metal in said second chamber at a lower temperature than that in the melting chamber, the temperature being that which is best adapted for casting and finally withdrawing the metal in a fluid condition from the second chamber, and depositing it in regulated quantities into a suitable receptacle or receptacles.

In testimony whereof I affix my signature in the presence of one witness on the 6th day of April, 1920.

GEORGE HILLARD BENJAMIN.

Witness:

ELISE L. INGALLS.
